CLAIM

The ornamental design for a panelled door cupboard, as shown and described.

DESCRIPTION

FIG. 1 is a perspective view of a panelled door cupboard according to an embodiment of the present invention;

FIG. 2 is a front plan view of the panelled door cupboard shown in FIG. 1;

FIG. 3 is a left plan view of the panelled door cupboard shown in FIG. 1, the right plan view is a mirror image of the left plan view; and,

FIG. 4 is a top plan view of the panelled door cupboard shown in FIG. 1.

The panel insets of the doors of the panelled door cupboard of my design may be transparent, translucent, opaque, or reflective.

The broken lines shown herein form no part of the claimed design.
